DESIGN FOR A MOBILE FOOD SERVICE UNIT

John C. Dinsmore, Chicago, Ill., assignor to Dinsmore Associates, Inc., Chicago, Ill., a corporation of Illinois

Application March 1, 1941, Serial No. 99,280

Term of patent 3½ years

To all whom it may concern:

Be it known that I, John C. Dinsmore, a citizen of the United States, residing at 5844 Stony Island Avenue, Chicago, in the county of Cook and State of Illinois, have invented a new, original, and ornamental Design for a Mobile Food Service Unit, of which the following is a specification, reference being had to the accompanying drawing, forming part thereof.

The single figure is a view in perspective of a

mobile food service unit embodying my new design.

The end of the mobile unit not shown in the drawing as well as the rear portion is substantially plain, while the bumpers at both ends, as well as the front and rear, are similar.

I claim:

The ornamental design for a mobile food service unit, substantially as shown and described.

JOHN C. DINSMORE.
